UNITED STATES PATENT OFFICE.

RUDOLF FRITSCH, OF DRESDEN, GERMANY.

DEVICE FOR MOVING CURTAINLIKE ROUNDHORIZONS.

Application filed June 20, 1923. Serial No. 646,721.

To all whom it may concern:

Be it known that I, RUDOLF FRITSCH, engineer, a subject of the Republic of Prussia, German Republic, and resident of 81 5 Wienerstrasse, Dresden, Republic of Saxony, Germany, have invented a new and useful Improvement in Devices for Moving Curtainlike Roundhorizons, of which the following is a specification.

10 The present invention has for its object an improvement of curtain-like horizons used in theatres of that kind in which a conical drum supporting the web or cloth is driven by a rope wound on the drum and 15 the latter is raised or lowered for a distance corresponding to the thickness of said rope on each revolution of the drum.

Now the novelty of the round-horizon moving device of the kind hereinbefore 20 stated consists of the driving-rope or the horizon-rope carrying the web or cloth is driven in alternate directions by a windlass or drum. In case the free extremity of the 25 horizon-rope carrying the web or cloth acts as a driving-rope of the conical drum, said rope is driven by two windlasses alternately engaging or disengaging in accordance with the direction of their rotation. A weighted 30 pulley or disc carrying a loose rope is arranged between windlasses and tightens the rope.

In the accompanying drawing forming part of this specification, and wherein like letters of reference indicate corresponding 35 parts in the several views—Figs. 1 and 2 are longitudinal elevations of a curtain-like round-horizon moving device and a modification of the same. Fig. 3 is a vertical section of the device showing the drum in the 40 position at the beginning of the winding up of the rope. Fig. 4 is an elevation partly in section of the device showing the part in position after the winding up of the round-horizon.

45 The rope used in combination with the object of the present invention diagrammatically shown in the drawing is driven or moved by a windlass such as generally used in vessels, or for moving or displacing rail-way-cars. In view of the fact that the rope used in the device forming the object of the invention is permanently wound up and off at the same place it is not necessary to omit pulley-blocks in the illustrations.

55 For tightening the single rope, Fig. 1,

the extremities of which are fastened to the conical drum *b* used for supporting the round-horizon *a*, two windlass drums *b* and *c* are provided arranged on a common shaft. Suitable means are employed whereby one 60 of said drums automatically couples itself to the shaft depending upon the direction of the rotation of the shaft, whereas the other drum is disengaged.

The rope running, according to the position shown in Fig. 1, off the coupled windlass, is guided around a weighted compensating-pulley *e* and around the disengaged windlass from which said rope runs into the race of the round horizon *a*. The compensating-pulley *e* automatically takes up 70 the resulting taut-rope or furnishes a corresponding length of the rope in case it is shortened. During the rotation of the shaft in an opposite direction the windlass *d* disengaged up to this time is automatically 75 coupled, whereas the windlass *c* in operation before is disengaged. The windlass *d* now coupled or engaged immediately acts on the rope to tighten it whereby a starting of the 80 round-horizon by jerks occurring with a slackened rope is obviated.

In the device shown in Fig. 2 two separate ropes are used each of them being fastened by one extremity to the conical drum *b* used for supporting the web or cloth of the round-horizon. The other rope serves to drive the conical drum. In this modified device only one windlass *c* need be employed. The free extremities are as may be 90 required alternately laid on the windlass and the rope winding down is kept taut by hand.

As seen in Figs. 3 and 4, *g* is an elongated race provided with corresponding notches and rigidly connected with a ground frame *h*. In this frame two guide bars *i* partly provided with teeth are inserted; a support *l* is slidable on said bars. This support is rigidly connected with the spindle *k* provided in its upper part with a longitudinal groove in which a rack *m* is inserted. The thread of the rack is of a pitch corresponding to the thickness of the rope. A nut *n* carrying the cone *b* engages the thread of the spindle *k* whereas the cone *b* carries on its upper or front surface the guide-box *o* engaging a recess provided in the rack *m*. Said rack meshes with the wheel *p* fastened to the spindle *q* journaled in the support *l*. 110

On the extremities of this spindle there are small wheels engaging the teeth of the guide-bars *i*, the diameters of said small wheels being in a ratio to the diameter of the wheel *p* corresponding to the stopping of the cone *b*.

Said cone *b* is rotated in the manner described by drawing or pulling the driving rope wound on it and fastened to it by the upper extremity of the rope mentioned with the result that the rope fastened on the lower extremity and carrying the round-horizon is wound up. Simultaneously the cone *b* moves downwards during each of its revolutions by the nut *n* rotating together with said cone on a length corresponding to the thickness of the rope. During said rotation the box *o* correspondingly takes with it the rack *m* in a downward direction rotating the wheel *p* and the small wheels *q* whereby the support *l* and with it the spindle *k* is, together with the cone *b*, horizontally displaced in such a manner that the distance between the slide and the race-shank *g* is not altered.

I claim as my invention:

1. In a device of the kind described a conical drum, a rope passing round said drum and having a horizontal portion for supporting a web or curtain, devices for winding said rope upon the said drum and unwinding the same therefrom, and means for displacing said drum so that the line on which the rope winds upon and unwinds from the said drum is a stationary one.

2. In a device of the kind described a conical drum, a rope passing round said drum and having its extremities secured therein, the said rope having a horizontal portion for supporting a web or curtain, a windlass for winding the rope upon the conical drum and unwinding the rope therefrom, and means for displacing the said drum so that the line on which the rope

winds upon and unwinds from the said conical drum is a stationary one.

3. In a device of the kind described a conical drum, a rope passing round said conical drum with the ends thereof secured in the conical drum, and the rope having a portion running horizontally for supporting a web or curtain, windlasses by which the rope is wound upon and unwound from the said drum to turn the same, and means for displacing said drum both laterally and longitudinally of its axis, whereby, the line on which the rope winds upon and unwinds from the said drum is a stationary one.

4. In a device of the kind described a conical drum, a frame, guide-bars connected to the said frame, a support slidable on the guide-bars, a spindle attached to the said slidable support, and upon which the said conical drum is revolvable, a rack associated with the said spindle, a wheel meshing with the rack, a shaft upon which the said wheel is mounted, the shaft being journaled in the said slidable support, gears on the said shaft meshing with teeth on the said guide-bars, a race shank, a rope passing through the said race shank, and around the said conical drum with the ends thereof fixed in the conical drum, the said rope having a horizontally disposed portion for the support of a web or curtain, and means for moving the said rope in alternate directions to turn the said conical drum, first in one direction and then in the other, whereby, in turning the conical drum the same is shifted both laterally and longitudinally of its axis, to cause the line on which the rope winds upon and unwinds from the said conical drum to be a stationary one.

In testimony that I claim the foregoing as my invention, I have signed my name this 2nd day of June, 1923.

RUDOLF FRITSCH.
